UNITED STATES PATENT OFFICE.

OREN N. LANNING, OF BARNARD, MISSOURI.

LIFTING MECHANISM FOR AERIAL VESSELS.

Application filed July 25, 1921. Serial No. 487,245.

To all whom it may concern:

Be it known that I, OREN N. LANNING, a citizen of the United States, residing at Barnard, in the county of Nodaway and

5 State of Missouri, have invented a certain new and useful Improvement in Lifting Mechanism for Aerial Vessels, of which the following is a complete specification.

This invention relates to aeroplanes of 10 the helicopter type and my object is to produce a heavier-than-air machine which will ascend or descend under its own power.

Another object is to produce a machine of 15 this character having a plurality of propellers disposed to stabilize or maintain the machine in a horizontal position, and which will not capsize should it happen that one of the units of its power cease to function.

A further object is to produce a machine 20 of simple, strong, durable, efficient and inexpensive construction and in order that it may be fully understood, reference is to be had to the accompanying drawings, in which:—

25 Figure 1 is a side view of the machine.

Figure 2 is a top plan view of the same.

Figure 3 is a section on the line III—III of Figure 1.

In the said drawings, where like reference 30 characters identify corresponding parts in all of the figures, 1 and 2 comprise a pair of substantially rectangular frames placed in superposed relation, each being provided with a pair of diagonal brace members 3.

35 The corners of each of the frames 1 and 2 are formed with bearings 4 for a purpose hereinafter described.

Suspended from the braces 3 of the lower frame member 2, by means of four posts 5, 40 is an engine and passenger sustaining platform 6, cut away along its side margins as at 7 to offer less wind resistance when the machine is vertically ascending or descending, and it is also formed with a series of 45 openings 8 for the same purpose. The four corners of platform 6 are formed with bearings 9 which are vertically below the bearings 4 above described and journaled in said bearings 4 and 9 are two pairs of vertical 50 shafts 10 and 11, said shafts being provided along their length between frames 1 and 2, with series of oppositely-projecting propeller blades 12, increasing in length from the lower cone to the upper cone as will be

55 clearly apparent by reference to Figure 1. This construction of the series of blades is

adopted in order that each blade shall in succession cut into an undisturbed column of air and will thus exert a greater lifting force than could otherwise be obtained.

60

Mounted on platform 6 are a pair of engines E, of any suitable character, provided with shafts 13 equipped at their ends with gear wheels 14 meshing with gear wheels 15 mounted on and near the lower ends of 65 shafts 10. It will thus be apparent that power applied to said gear wheels 14 will rotate the vertical shafts 10.

In order to transmit power from said shafts 10 to shafts 11, the former are provided at any suitable points, but preferably a slight distance below frame 2, with gear wheels 16 which mesh with gear wheels 17 keyed on the ends of diagonal shafts 18, one shaft being located slightly above the other.

70

75 Shafts 18 are journaled near their opposite ends in the posts 5 and are provided at their ends opposite from gear wheels 17, with gear wheels 19, which mesh with gear wheels 20 keyed to vertical shafts 11. It 80 will be noted in this connection that the shafts 10 are diagonally opposite to the shafts 11, this construction being adopted in order to stabilize the machine should one of the engines cease to function during a flight.

85

Two pairs of semicircular partition members 21 are fitted between frames 1 and 2 and around the blades 12, it being noted that the edges of said partitions are cut at an angle in order to enclose the larger of said 90 blades. These partitions are provided to form divisions between each series of propellers in order that the air currents set up shall not conflict with each other, and it will be seen that this construction forms a central passage way. To protect the operator of the machine from the downward current of air which will flow when the machine is ascending, a cone-shaped deflector 22 is secured centrally of the machine to the lower 100 pair of diagonal braces 3, the shafts 18 passing diagonally through said cone. The driver's seat 23 will be mounted on a tripod 24 secured to the platform 6 and directly below the cone above described, and the 105 driver will thus be conveniently located to the engines.

It will be apparent that the speed of the engines may be controlled so as to equalize the strain on the frame, and also that the 110 platform may be equipped with any suitable landing gear to absorb the shock incident to

landing. In operation the speed of ascent or descent will be entirely under the control of the operator through regulation of the engine speed.

5 From the above description it will be apparent that I have produced a machine of the character described which possesses all of the features of advantage pointed out as desirable and while I have described and 10 claimed the preferred embodiment of the same, I reserve the right to make all changes properly falling within the spirit and scope of the appended claims.

I claim:

- 15 1. A helicopter, comprising a pair of superposed spaced frames, a platform below said frames, a seat centrally-located on the platform, a vertical shaft journaled in each corner of the framework constituted by said 20 frames and platform, means for driving the shafts, propellers on the shafts between said frames, partitions between said frames and propellers, and a conical deflector between the seat and said frames to protect the 25 driver from the blast of air set up by the propellers.

2. A helicopter, comprising a rectangular

framework, vertical shafts journaled in the framework, power-transmitting connections between diagonally-opposite pairs of said 30 shafts, propellers on said shafts, partitions interposed between the propellers and curved concentrically of the respective shafts, the partitions for and between diagonally-opposite propellers being oppositely-bowed and respectively secured to the 35 partitions for and between the other pair of diagonally-opposite propellers, and a motor for each pair of diagonally-opposite propellers. 45

3. A helicopter, comprising a pair of superposed rectangular frames, propeller shafts journaled in the corners of said frames, a plurality of propeller blades carried by said shafts and decreasing in length 40 from the undermost to the uppermost, a platform suspended from the lowermost frame, a pair of engines carried by said platform and each adapted for rotating a pair of shafts, and a partition interposed 50 between the blades of the respective shafts.

In witness whereof I hereunto affix my signature.

OREN N. LANNING.
